SKIRT MARKER

Grace M. MacFarlane, Rockford, Ill.

Application January 9, 1946, Serial No. 640,062

1 Claim. (Cl. 33—9)

1

This invention relates to devices for marking skirts and the like, to establish a hem line thereon.

A general object is to provide a skirt marker for gripping and holding a measuring stick and a piece of chalk in the proper relation without the use of screws or other complicated clamping means.

A more detailed object is to provide a skirt marker in which the clamp for the chalk and measuring stick are each formed by parts of a resilient coil of wire.

Another object is to form both clamps from a single piece of wire.

Other objects and advantages of the invention will become apparent from the following detailed description taken in connection with the accompanying drawings, in which

Figure 1 is an elevational view of a skirt marker embodying the present invention, illustrating its manner of use.

Fig. 2 is an enlarged view of the marker shown in Fig. 1.

Fig. 3 is a perspective view of the chalk and stick supporting device of the marker.

In the drawings, the improved device 10 is adapted for use in gripping a flat piece 11 of ordinary tailor's chalk and a yardstick 12 and holding the two firmly in planes perpendicular to each other. Generally stated, the device comprises two clamps 13 and 14, respectively formed by bending opposite end portions 15 and 16 of a resilient wire, preferably steel, into loops or helical coils, each comprising more than one revolution. The coils are disposed with their edges close together and are connected rigidly by the center 17 of the wire, by which the coils are held in planes perpendicular to each other. While the coils may be of any desired shape, they are preferably circular, as shown, and of diameters about equal to the widths of the yardstick and the chalk.

The wire portion 16 forming the clamp 14 comprises nearly two full convolutions, so that its end 18 terminates just short of the connecting part 17. Thus, the rounded outermost parts 19 and 20 of the coil form the opposed jaws of the clamp 14 for gripping opposite sides of the chalk piece 11. The coil is wound loosely so that the two loops 19 and 20 are axially spaced apart a distance less than the thickness of the chalk so that the latter may be guided in between the loops and clamped firmly, due to the resiliency of the wire.

The other coil forming the clamp 13 is formed

5 in a similar way to provide clamping parts 21 and 22. Actually, the two coils may be duplicates, as shown, because of the fact that the yardstick ordinarily used in marking skirts is of substantially the same thickness as an ordinary piece of tailor's chalk. Thus, the two clamps may be used alternatively to receive either the chalk or the measuring stick.

10 To provide for holding the chalk 11 in a plane perpendicular to the yardstick, the two coils are twisted relative to each other, and the connecting portion 17 is thus bent to hold the coils at right angles to each other.

15 Preparatory to using the device, the chalk 11 is pressed into one of the clamps, leaving its edge 23 projecting, as shown in Fig. 2. The other clamp is forced onto the yardstick, and the device 10 as a whole is slid along the stick until the plane 20 of the chalk edge 11, as measured on the scale of the yardstick, is spaced from the end of the stick a distance equal to the desired spacing of the skirt hem from the floor. With the stick resting on the floor, as shown in Fig. 1, the chalk may be pressed against the skirt 24 to form a 25 mark 25 indicating the desired hem line.

20 The device, being formed entirely of wire, is simple and inexpensive in construction, and yet may be attached to the chalk and yardstick quickly and conveniently. The two are held effectively in the proper relation without the necessity of adjusting screws or other clamping devices.

25 It will be apparent that the coil 15 constitutes one portion of the length of the wire while the other coil 16 constitutes the remaining portion of the wire so that the two coils are closely spaced together with their peripheries substantially in contact. This arrangement minimizes the chances of bending one coil relative to the 30 other and insures that the chalk 11 will always be held accurately positioned in relation to the measuring stick 12.

35 I claim as my invention:

40 In a skirt marker, a piece of resilient wire having its opposite end portions bent to form two coils disposed in perpendicular planes with one coil comprising one portion of the length of said wire and the other coil comprising the remainder of said wire, one of said coils having its axis disposed vertically and the other having its axis disposed horizontally, each of said coils comprising a plurality of convolutions with the convolutions of one coil being axially spaced to receive and clamp a piece of chalk with the latter 45 projecting outwardly horizontally, and the other

coil having axially spaced convolutions for gripping a vertically extending measuring stick and holding the same at right angles to the chalk.

GRACE M. MacFARLANE.
